UNITED STATES PATENT OFFICE.

LLEWELLYN R. JONES, OF BRIGHTMOOR, MICHIGAN.

NECKTIE HOLDER.

Application filed April 17, 1924. Serial No. 707,302.

To all whom it may concern:

Be it known that LLEWELLYN R. JONES, a subject of the King of England, residing at Brightmoor, in the county of Wayne and 5 State of Michigan, has invented new and useful Improvements in Necktie Holders, of which the following is a specification.

The object in view is to provide a device suitable for use as a form upon which a 10 four-in-hand or similar necktie may be tied or knotted to present the desired display and having means for engagement with the collar and the collar button or stud, more particularly when the collar is of the turn 15 over or turn down type to support the tie in proper position, said holder being of such a construction as to adapt it to be disconnected from the collar button and collar without removing, loosening or disarranging 20 the tie, and of being subsequently replaced rapidly under the same conditions; and with this object in view the invention consists in a construction and combination of parts of 25 which a preferred embodiment is shown in the accompanying drawings, wherein:—

Figure 1 is a view of a tie holder embodying the invention having arranged thereon a tie knotted in condition for use and applied in the operative position to a collar.

30 Figure 2 is a similar view showing the holder and tie disconnected from the collar.

Figure 3 is a similar view showing the tie loosened to expose the intermediate or central portion of the holder.

35 Figure 4 is a side view of the holder showing the tie in place thereon.

Figure 5 is a view of the holder disconnected from the tie.

The holder consists essentially of a button 40 plate 10 provided with a key hole slot 11 suitable for engagement with the collar button or stud and having at its upper end laterally projecting curved collar engaging

wings 12 adapted to be inserted between the 45 folds of a collar close to the fold line, and

pivottally mounted in a clip 13 projecting forwardly from the plate is a spring arm 14 adapted to bear against the head or outer end of the collar button or stud indicated at 15 for maintaining the holder in proper 50 relation with the button, said tongue being deflected forwardly at its free end to form an ear 16 and being extended at its pivotal end beyond the pivot 17 to form a finger 18 adapted to bear against the surface of 55 the plate 10 to hold the arm in either its normal or inoperative position, so that when the plate is being engaged with the button the free end of the tongue may be sprung outward as shown in dotted lines in Figure 60 4 and may then be forced rearwardly into contact with the button as shown in full lines in said figure to be concealed by the bow or knot 19 of the tie which is looped over the wings 12 as indicated in Figure 3 or in any 65 preferred manner to suit the appearance of tie desired by the wearer.

When the tie is drawn taut as indicated in Figures 1 and 2 the looped or knotted portion thereof lies in front of the holder in 70 the space between the front edges of the collar and is in turn held in proper position with relation to the collar.

Having described the invention, what is 75 claimed as new and useful is:—

A necktie holder having a collar button or stud engaging plate provided with lateral wings for engagement with the fold of a turn over collar, said wings forming means for engagement by the loop or knot of the 80 tie, and a spring tongue carried by the plate for terminal engagement with the forward end of the button or stud engaged by the plate, said tongue being pivotally mounted upon the plate and being provided with 85 means for yieldingly holding the same in its operative and inoperative positions.

In testimony whereof he affixes his signature.

LLEWELLYN R. JONES,
